United States Patent Office.

JULIA W. D. PATTEN, OF NEW YORK, N. Y.

Letters Patent No. 82,869, dated October 6, 1868.

IMPROVED ICE-PRESERVER.

The Schedule referred to in these Letters Patent and making part of the same.

TO ALL WHOM IT MAY CONCERN:

Be it known that I, JULIA W. D. PATTEN, of the city, county, and State of New York, have invented a new and improved Ice-Preserver; and I do hereby declare that the following is a full, clear, and exact description of the construction and operation of the same, reference being had to the accompanying drawings, making a part of this specification, in which—

Figure 1 is a vertical section.

Figure 2 is a similar section, showing another form of box.

The object of this invention is to provide a neat and cheap receptacle, which will protect ice, food, medicines, &c., from the action of the air; and having its walls made of a substance, herein described, which is a remarkable non-conductor of heat, and will maintain around the enclosed contents of the receptacle a uniform temperature, thereby preventing the melting of the ice, and the decomposition of the food, medicines, chemicals, or other article to be preserved.

In the drawings, A indicates a dome-shaped box or cover, fitting air-tight around and upon a detachable bottom, B, the bottom having a vertical flange, b, around its rim, so as to constitute a shallow pan, in which the ice, i i, may be placed, and the food or other articles being placed upon the ice, as seen at F. The box or cover A may be provided with a handle, C, and may be made in any other convenient form, if preferred, and may be ornamented at pleasure.

The bottom or pan B, fig. 1, is composed of tin, iron, silver, wood, or any other material that will be water and air-tight.

The walls and roof of the cover A are composed of paper and pasteboard, a, on the outside, lined with mica, a', on the inside, the mica being attached to the paper walls by some adhesive substance, or being stitched, riveted, or otherwise suitably fastened thereto.

The object of the paper or pasteboard is to prevent the action of the outside air upon the ice, food, &c., and to furnish a strong non-conductor of heat, paper being one of the best known substances for that purpose. The object of the mica lining is to prevent the taste of the food, medicines, &c., from being affected by the paper or pasteboard. Neither substance, independent of the other, will answer the purpose of preserving the ice and other articles from the action of the air and of heat or cold, without having their taste and smell sensibly affected, but combined, as described, and employed as a material for the construction of covers, boxes, &c., they answer the purpose admirably.

It has been found by practical test, that in a receptacle similar to that shown in fig. 1, ice will last one-third or one-half longer than in any other ice-preserver now in common use.

The form of the box or cover is, of course, not a material part of the invention. The form shown in fig. 1, and herein described, is believed to be as simple, cheap, and convenient as any, for preserving ice in connection with articles of food, but for preserving other substances, such as dentifrices, soaps, medicines, toilet and other perfumed articles, &c., other forms may be more conveniently employed, which it is unnecessary for me to describe or show.

Having thus described my invention, what I claim as new, and desire to secure by Letters Patent, is—

An ice-preserver, consisting of a box or cover, having an outside wall of paper or pasteboard, lined with mica on the inside, substantially as described.

JULIA W. D. PATTEN.
